UNITED STATES PATENT OFFICE.

JOSEPH F. MOODY, OF AUGUSTA, KANSAS.

WELL-DRILLING APPLIANCE.

1,322,809.

Specification of Letters Patent. Patented Nov. 25, 1919.

Application filed March 15, 1919. Serial No. 282,829.

To all whom it may concern:

Be it known that I, JOSEPH F. MOODY, a citizen of the United States, residing at Augusta, in the county of Butler and State 5 of Kansas, have invented new and useful Improvements in Well-Drilling Appliances, of which the following is a specification.

This invention relates to improvements in well drilling appliances, and more particularly an appliance for screwing and unscrewing the casing or pipe sections.

The invention has for its object to provide a novel and improved power-driven device for the purpose stated, which is rapid in 15 operation and easily controlled, and to this end it consists in a novel combination and arrangement of parts to be hereinafter described and claimed.

In order that the invention may be better 20 understood, reference is had to the accompanying drawings forming a part of this specification, and in said drawings—

Figure 1 is a side elevation of the appliance;

Fig. 2 is a plan view thereof;

Fig. 3 is a cross section on the line 3—3 of Fig. 1, with some of the parts shown in elevation;

Fig. 4 is a sectional detail of a coupling;

Fig. 5 is an end view of said coupling;

Fig. 6 is a plan view of a gripping device;

Fig. 7 is a plan view of another gripping device;

Fig. 8 is a section on the line 8—8 of 35 Fig. 2, and

Fig. 9 is a section on the line 9—9 of Fig. 2.

Referring specifically to the drawings, 10 denotes a platform which is carried by a 40 wheeled supporting frame which holds the apparatus in operating position and facilitates transportation from one job to another. The frame is composed of a cross beam 11 from the ends of which rise standards 12 45 connected at the top by a cross beam 13 which supports the forward end of the platform 10. Diagonal braces 14 extend between the beam 11 and the standards 12, and between the said beam and the braces extend 50 struts 15. The beam 11 also supports a pair of laterally spaced longitudinal bars 16 connected at their rear ends by a cross beam 17 and here supporting a pair of standards 18 connected at the top by a cross beam 19 and 55 supporting the rear end of the platform 10. The bars 16 project at their forward ends

from the beam 11 and here carry certain mechanism to be presently described. Between the bars 16, the beams 11 and 17 support a tongue 20 which projects a suitable 60 distance from the rear end of the frame so that it may be attached to a motor vehicle similar to a trailer, whereby the entire appliance may be readily transported to or from the place of use, and from one job to 65 another.

The frame hereinbefore described is supported by two wheels 21 located at the forward end thereof. In the standards 12 are guide ways in which are mounted spring-backed blocks 22 which carry the spindles 23 of the wheels 21. Into the tops of the standards are threaded screws 24 which bear on blocks 25 located above the blocks 22, springs 26 being interposed between said 75 blocks. The frame is therefore cushioned and jars are taken up by the springs when the appliance is being transported. It will also be evident that the frame can be leveled when the appliance is placed in operative 80 position, this being done by the screws 24. From the rear faces of the slide blocks 22 extend pins 27 which seat in guide slots 28 in the struts 15 and also in slots 29 in the standards 12 back of the guideways in which 85 the slide blocks seat.

In the forward end of the platform is a circular opening 30 which is shouldered, as shown at 31, to seat a rotary horizontally positioned table 32 having its top formed 90 with a circular rack 33. This turn-table is formed with a central opening 34 to accommodate the casing section 35 to be operated on. The opening extends to and opens through the edge of the table for the entry 95 and exit of the casing section by moving the appliance bodily to carry the table transversely of the casing section. The turn-table 32 has a removable section 36 normally closing the outer end of the opening 100 34, and upon removing said section, the casing section 35 or other work to be operated on may enter the opening. To the top of the table is detachably secured a work guide plate 37 for the casing section, said plate 105 having a slot 38 through which the work passes. Various guide plates, according to the diameter of the casing section to be operated on, will be provided.

The table 32 carries a device for gripping 110 the casing section 35. This gripping device comprises a segmental head 39 closed up by

a link or gate 40 which is pivoted at one end to the head and has its other end detachably fastened to the corresponding side of the head. Inside the head are two opposite, pivoted dogs 42 having teeth to engage the casing section. The free ends of the dogs are straddled by the branches 46 of a fork the stem 47 of which is pivoted at 48 to the head 39. When the fork is swung 10 in one direction one of the dogs 42 is forced into gripping engagement with the casing section, and when the fork is swung in the opposite direction, the other dog takes hold. This gripping device is substantially the 15 same as the one disclosed in my previous application filed August 10, 1918, Serial No. 249284.

The fork stem 47 is slidably mounted on a vertical rod 49 carried by the turn-table 20 32 and depending from the bottom thereof directly beneath the rack 33. From the bottom of the table also extends a stirrup 50 which supports the lower end of the rod 49, and between the fork stem 47 and the 25 stirrup a spring 51 is coiled around the rod, this spring holding the stem elevated on the rod. The stem, however, is free to slide on the rod so that the gripping device 39 may follow the casing section 35 down or up as 30 it is being screwed down or unscrewed. Downward movement of the stem is resisted by the spring and hence the gripping device is yieldingly supported, and its downward movement is cushioned. Different 35 sized casing sections can be operated on by using the different sized gripping devices; or the latter can be adjusted for casing sections of different diameters by using different sized dogs 42 or fitting the same with 40 bushings.

The rear end of the stem 47 is divided to straddle a guide block 47^a through which the rod 49 passes, said block having side grooves in which the end sections of the 45 stem seat, and said sections are connected at their rear ends by a plate 48^a between which latter and the block is interposed a spring 49^a. The gripping device is therefore free to yield rearwardly, and it is normally held advanced by the spring 49^a.

Beneath the hereinbefore described gripping device is a second gripping device 51 constructed in substantially the same manner, but having no vertical sliding movement, and having its gate 52 held closed by a lever 53 so that it can be easily opened. This lower gripping device does not revolve and its function is to grip and hold the lower casing section 54, or the collar 54^a, 55 while the upper section 35 is being turned to screw on or be unscrewed. The fork stem 54' of the lower gripping device is supported by a block 55 which is pivoted, as shown at 56, on a cross bar 57 carried by 60 forward extensions 58 of the bars 16, in ad-

vance of the cross beam 11. The fork stem is longitudinally slotted as shown at 59 to straddle the block 55, and between the block and a cross bar 59^a closing up the rear end of the slot is interposed a coiled spring 60 70 which tends to hold the gripping device normally advanced toward the casing section 54, but allows it to yield rearwardly, and as the pivot 56 allows the gripping device to swing laterally, it readily accommodates itself to the part to be gripped. 75

The forward extremities of the bars 58 are flared so that the casing section 54 may readily enter therebetween and they also carry a recessed guide plate 61 similar to 80 the plate 37.

The frame bars 16 support a steam engine or other suitable fluid-pressure motor 62. On the drive shaft 63 of this motor is a bevel gear 64 which is in mesh with bevel 85 gears 65 on aligned shafts 66 having pinions 67 meshing with spur gears 68 on short shafts 69 provided with pinions 70 which are in mesh with the rack 33. A suitable clutch 71 is provided for connecting the 90 gear 64 to the shaft 63, and for disconnecting the same. The bearings for the various shafts are all carried by the platform 10.

It will be evident from the foregoing that when the upper casing section 35 is engaged by the gripping device 39, and the lower section 54 or the collar 54^a by the gripping device 51, said upper section will be screwed or unscrewed when the clutch 71 is engaged, the turn-table 32 being rotated through the 100 gearing hereinbefore described, and as the gripping device 39 is carried around with the table, the casing section is screwed on or unscrewed according to the direction the table is being rotated, the direction of rotation being governed by the engine 62 which is reversible; or any other expedient may be resorted to for reversing the direction of rotation of the driving means. 105

The turn-table 32 can also be rotated by 110 a jerk line 72 attached to the crank of some rotatable power-driven member of the drilling machinery, as in case, Serial No. 249284, filed Aug. 10, 1918. The line 72 will be attached to a lever 75 carrying a spring pawl 115 which engages a ratchet wheel 76 on one of the shafts 69. The line pulls the ratchet lever in one direction and it is pulled back by a line 77 having a weight 78 attached to its end. The platform 10 carries a guide pulley 79 for the weighted line 77. A ratchet lever may be attached to each shaft 69 so that a continuous rotary motion may be given the table by having one lever make a working stroke while the other lever makes 125 the return stroke.

As the entire appliance is portable and mounted on a truck, it can be readily transported and placed in position for use. The forward end of the tongue 20 may be sup- 130

ported by a block 80 carried by an arch 81, the block having an aperture in which the tongue loosely seats so that the appliance may be shoved forward or backed on or off 5 the casing sections. The block also serves to hold the appliance so that it cannot swing around when in operation. The block 80 works in vertical guides 82 and is adjustable by a screw 83 to level the appliance. The 10 arch 81 will be bolted to the floor 84 of the rig. The forward ends of the bars 58 rest on blocks 85 when the appliance is in use.

In order to protect the engine from damage by excessive loads liable to be thrown 15 thereon, the driven member of the clutch 71 is carried by a hollow shaft 86 loose on the shaft 63 and having a flanged pulley 87. On the shaft 63 is fast a pulley or disk 88 which is engaged by friction bands 89 carried 20 by the inside of the flange of the pulley 87. The ends of the bands are adjustably secured to ears 90 on the pulley flanges by bolts 91, so that the grip of the bands on the pulley 88 may be adjusted. The motion of 25 the shaft 63 is therefore transmitted to the shaft 86 through a slip coupling, and if an excessive load is thrown on the shaft 86, the pulley 88 slips. The friction bands 89 can be adjusted to hold whatever load the engine 30 is designed to stand.

The pivot bolts 39^a of the dogs 42 also serve to secure the gate or link 40. One of these bolts is tubular to receive a removable pin 40^a for holding the detachable end of the 35 gate.

I claim:

1. A well-drilling appliance comprising a supporting frame, a turn-table carried by said frame, a work gripping device carried by the turn-table, a pivoted block carried by 40 the supporting frame, a work-gripping device slidably supported by said block and yieldable transversely of the work, and means for operating the turn-table.

2. A well-drilling appliance comprising a 45 portable wheeled supporting frame, a turn-table carried by said frame, a work gripping device carried by the turn-table, means for operating the turn-table, a draft tongue extending from the frame, and means engageable with the tongue for holding the 50 frame stationary.

3. A well-drilling appliance comprising a portable wheeled supporting frame, a turn-table carried by said frame, a work gripping 55 device carried by the turn-table, means for operating the turn-table, a draft tongue extending from the frame, and vertically adjustable means engageable with the tongue for holding the frame stationary. 60

4. A well-drilling appliance comprising a supporting frame, a turn-table carried by said frame, a work gripping device carried by the turn-table, a work gripping device carried by the supporting frame beneath the 65 first mentioned gripping device, and yieldable transversely of the work, and means for operating the turn-table.

In testimony whereof I affix my signature.
JOSEPH F. MOODY.
